(57) **CLAIM**

The ornamental design for a handle for a kitchen knife, as shown and described.

DESCRIPTION

FIG. 1 is a front, bottom, right side perspective view of a handle for a kitchen knife in accordance with our design; FIG. 2 is a front, top, right side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines illustrate portions of the handle for a kitchen knife that forms no part of the claimed design.

1 Claim, 7 Drawing Sheets
